UNITED STATES PATENT OFFICE.

PAUL OTTMAR WALCH, OF PARIS, FRANCE.

WIRE FASTENING FOR BOTTLE-STOPPERS.

SPECIFICATION forming part of Letters Patent No. 402,370, dated April 30, 1889.

Application filed August 8, 1888. Serial No. 282,250. (No model.) Patented in France March 13, 1888, No. 189,318.

To all whom it may concern:

Be it known that I, PAUL OTTMAR WALCH, a citizen of the German Empire, residing at Paris, France, have invented certain new and useful Improvements in Wire Fastenings for Bottle-Stoppers, (for which I obtained a patent in France, March 13, 1888, numbered 189,318,) of which the following is a specification.

10 This invention relates to a wire fastener for bottle-stoppers made from one continuous length of wire, and which can be opened without cutting the wire.

15 The invention consists in the various features of improvement more fully pointed out in the claim.

20 In the accompanying drawings, Figure 1 is a perspective view of my improved wire fastener. Fig. 2 is a side elevation of the same when closed, showing it applied to a bottle. Fig. 3 is a similar elevation, but showing it open.

25 My improved wire fastener is made from one continuous length of wire; but it will be necessary to designate the different parts of this wire by different letters of reference, so that the drawings may be more easily followed.

Beginning at the point *a*, the wire has a straight section, *b*, and is then bent upon itself to form the twist *c*, with large open-end loop, *d*. From twist *c* the wire is again straight, as at *e*, then runs up as a single corrugated shank, *f*, terminating in a straight portion, *g*. From portion *g* the wire is run down and up to form the corrugated shank *h*, having a loop, *h'*, at its foot. In similar man-

ner the wire is continued to form straight portion *i*, corrugated shank *j*, with loop *j'*, straight portion *k*, corrugated shank *l*, with loop *l'*, and straight portion *m*. From here 40 the wire is bent down, as at *n*, and intertwined with shank *f* to form corrugated shank *n*. Thence the wire *o* is passed through the loops *h' j'*, terminating at point *p*.

The section *b* is passed through the loop *l'*, 45 and the two ends *a p* may be intertwined, Fig. 2, to close the wire around the neck of a bottle, A. It will be seen that the portions *g i k m* form, in effect, a square frame resting upon the top of cork B, while the portions *b e o* form, in effect, a neck-wire. This neck-wire has the twist *c* with loop *d*. To remove the cork from a bottle, it is only necessary to untwist the portion *c*, Fig. 3, when the neck-wire will be so much enlarged as to permit 55 the slipping of the entire contrivance over the neck and cork.

What I claim is—

A wire fastener composed of a length of wire bent to form a series of twisted shanks 60 connected on top and terminating in loops at their lower ends, and to form a neck-wire which is provided with a twisted portion, *c*, and loop *d*, and which passes through the loops at the ends of the twisted shanks, sub- 65 stantially as specified.

In witness whereof I hereunto set my hand in presence of two witnesses.

PAUL OTTMAR WALCH.
